(57) **CLAIM**

The ornamental design for a beer faucet tap electric light switch, as shown and described.

DESCRIPTION

FIG. 1 is a perspective view of a beer faucet tap electric light switch showing my new design.

FIG. 2 is a right-side view of FIG. 1, the left-side view being a mirror image thereof;

FIG. 3 is a front view of FIG. 1.

FIG. 4 is a top view FIG. 1.

FIG. 5 is a bottom view of FIG. 1.

FIG. 6 is a rear perspective view of FIG. 1.

FIG. 7 is a perspective view of an alternative embodiment of the beer faucet tap electric light switch.

FIG. 8 is a right-side view of FIG. 7, the left-side view being a mirror image thereof;

FIG. 9 is a front view of FIG. 7.

FIG. 10 is a top view of FIG. 7.

FIG. 11 is a bottom view of FIG. 7; and,

FIG. 12 is a rear perspective view of FIG. 7.

My beer faucet tap electric light switch is characterized by using a beer faucet, shank and handle combination with an electric switch.
